CLAIM

The ornamental design for an adjustable chainsaw holder, as shown and described.

DESCRIPTION

FIG. 1 is a Front elevation view of the adjustable chainsaw holder;

FIG. 2 is a Left side elevation view of the adjustable chainsaw holder thereof;

FIG. 3 is a Right side elevation view of the adjustable chainsaw holder thereof;

FIG. 4 is a Top plan view of the adjustable chainsaw holder thereof;

FIG. 5 is a Bottom plan view of the adjustable chainsaw holder thereof;

FIG. 6 is a Front left isometric view of the adjustable chainsaw holder thereof;

FIG. 7 is a Front right isometric view of the adjustable chainsaw holder thereof;

FIG. 8 is a Back right isometric view of the adjustable chainsaw holder thereof;

FIG. 9 is a Back left isometric view of the adjustable chainsaw holder thereof; and,

FIG. 10 is a Front left isometric view of the adjustable chainsaw holder showing a chainsaw inserted in the holder. The dash-dash broken lines in FIG. 10 showing a chainsaw depict environmental subject matter that forms no part of the claimed design.

1 Claim, 5 Drawing Sheets
